CLAIM

The ornamental design for a converter for transmitting image and character data from a computer to a printer, as shown and described.

DESCRIPTION

FIG. 1 is a front elevational view of a converter for transmitting image and character data from a computer to a printer showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view thereof.

*FIG. 1**FIG. 2**FIG. 3*

FIG. 4

FIG. 5

FIG. 6

FIG. 7
